TRAFFIC SIGNAL

Elmer F. Waterbor, Detroit, Mich., assignor to
 Michigan Malleable Iron Company, Detroit,
 Mich., a corporation of Michigan

Application June 29, 1936, Serial No. 88,002

7 Claims. (Cl. 40—125)

The invention relates to traffic signals of that type in which a signal flag normally extends in upright position in the roadway, but is compressible by the wheels of vehicles passing thereover. It is 5 the object of the invention to obtain a substantial construction which will withstand the use and abuses to which it is subjected, which is easily depressed by the vehicle wheels without injury thereto, and which will remain in operative condition 10 for an indefinite period of time. With these objects in view, the invention consists in the construction as hereinafter set forth.

In the drawing:

Figure 1 is a section of a portion of the pavement showing my improved traffic signal positioned therein;

Figure 2 is an enlarged view of the operating mechanism;

Figure 3 is a transverse section;

Figure 4 is a plan view.

My improved signal comprises a normally upright plate or flag A, preferably having applied thereto the word "Stop" in plainly visible letters, as indicated at B. Also, if desired there may be 25 arranged on a portion of the surface a reflector unit C which will be illuminated by the headlights of an approaching car. This plate A is mounted on a bed plate D which is embedded in the pavement to be substantially flush with the upper surface 30 thereof and is firmly anchored thereto by suitable means, such as the bolts E at the corners. Extending transversely of this plate is the upwardly extending rounded housing F to which the plate A is attached by trunnions G. These 35 trunnions are preferably formed by a shaft extending completely through the housing and out from the opposite ends thereof, being attached to downwardly extending arms A' on the plate A. Centrally beneath the bed plate D and housing 40 F is a downwardly extending cylindrical housing H containing a slideable plunger I resiliently pressed upward by a spring J which seats on the bottom of the housing H. The upper end of the plunger I engages a cam K mounted on the shaft 45 G, which cam is so fashioned that the resilient pressure will turn it to a position where the plate A extends vertically upward. Thus whenever the plate A is pressed downward by the passage of a vehicle wheel thereover, the resilient pressure of 50 the plunger engaging the cam will restore it to its upright position.

One difficulty with the construction as thus far described is that the inertia of the plate A when returning to its upright position is sufficient 55 to carry the plate beyond this position.

Thus the plate depressed by the forward wheel of a vehicle might assume a position where its outer edge would strike the following rear wheel to the injury of the latter. It is, therefore, an important feature of my improvement that the flag or plate in returning is prevented from passing beyond its upright position, this being accomplished by the following construction.

L is a piston at the lower end of the plunger I which fairly closely fits the cylinder H. Within 10 the skirt of this piston L is the spring J and within this spring a tubular core member M depending from the upper head of the piston. This core member has at its lower end a seat N for a ball valve O which may be yieldably pressed towards the seat by a relatively light spring P. The chamber within the hollow core M is connected by a central port Q and laterally extending ports Q' with a space in the cylinder above the piston. Thus if the cylinder H is filled with liquid, this 15 will not interfere with the free downward movement of the plunger, as the valve O will be lifted from its seat and the fluid will flow through the hollow core member M and ports Q and Q' to the chamber above the piston. On the other hand, when the plunger moves upward the ball O will seat preventing return of fluid through the same channel. However, the fluid is permitted to slowly return through a restricted port R passing 20 through the head of the piston into the annular space in which the spring J is located. Thus in 25 operation the signal or flag A can be quickly depressed by the wheel passing over it, but its return is sufficiently retarded to limit the kinetic energy or inertial factor, so that the cam K will 30 stop it in upright position.

To maintain the mechanism in operative position it should be well lubricated and the best lubricating fluid will differ in viscosity from the best fluid for controlling the plunger or dashpot. I, therefore, preferably arrange a head S between the piston L and the upper end of the plunger I, this head being apertured for the passage of a plunger shank I' therethrough. The compartment above the head S is in communication with the chamber within the housing F through ports T through the head of the plunger so that any lubricating fluid in the housing F is free to pass through these ports into the chamber above the head S. This will permit of using 40 a different fluid within the housing F and upper portion of the cylinder H from that which is in the lower or dashpot portion of the cylinder and consequently the trunnions will be maintained 45 well lubricated.

In order to provide sufficient strength in the flag plate A to withstand the shocks it is of a substantial thickness and is further provided with a still thicker bead A² surrounding the central panel. Thus when the plate is flattened down upon the bed plate D, it will be extended upward therefrom equal to the thickness of the bead A² and might form an abrupt shoulder against which the wheel of the vehicle would strike. To avoid such effect, I have provided on opposite ends of the bed plate D transversely extending ramp portions U which on their outer sides slope upward from the level of the pavement and on their inner sides form an abrupt shoulder adjacent to the plate A when in depressed position. These ramp portions U serve to lift the wheel passing thereover so as to lessen the height that it must be subsequently raised to pass over the housing F. The space between the ramp and the housing is of such small dimension that the wheel will not materially drop in crossing the same. On the other hand, after the wheel has passed over the housing F and engages the depressed plate A, the ramp U will serve to gradually lower the wheel from off said plate to the pavement level.

To permit of assembly of the parts and to retain the same in proper relative position, the plunger I, together with its shank I', is separate from the piston L, the lower end of said shank bearing against said piston. The head S is apertured for the insertion of the shank I' therethrough and said head has a shouldered engagement S' with the cylinder H to prevent upward movement. The lower end of the cylinder H has a detachable head or plug V preferably having a tapered threaded engagement with said cylinder and provided with a detachable smaller plug V' through which fluid can be introduced. Thus all of the parts may be introduced through the lower end of the cylinder when the plug V is removed and when said plug is placed in position these parts will be held from disengagement.

What I claim as my invention is:

1. A traffic signal comprising a bed plate, a signal plate pivotally mounted on said bed plate and rockable from a perpendicular position to a position parallel and adjacent to said bed plate, resilient means for returning said signal plate to its upright position after the depression of the same, and means for positively retarding the speed of return and thereby preventing the swinging of said plate beyond the upright position during said return movement.

2. A traffic signal comprising a bed plate, a signal plate pivotally mounted on said bed plate and rockable from a perpendicular position to a position parallel and adjacent to said bed plate, a spring pressed plunger and cooperating cam for returning said signal plate to upright position, and a dashpot controlling the return movement preventing the swinging of the plate beyond the upright position.

3. A traffic signal comprising a bed plate, a signal plate pivotally mounted on said bed plate and rockable from a perpendicular position to a position parallel and adjacent to said bed plate, a housing beneath said bed plate, a spring pressed plunger within said housing, a cam connected to said signal plate engaging said plunger being adapted to depress the same when said plate is rocked downward and functioning to return the plate by the upward pressure of said plunger, and a dashpot within said housing for retarding

the upward movement of said plunger so as to prevent the swinging of said plate beyond its upright position.

4. A traffic signal comprising a bed plate, a signal plate pivotally mounted on said bed plate and rockable from a perpendicular position to a position parallel and adjacent to said bed plate, a housing beneath said bed plate, a spring pressed plunger within said housing, a cam connected to said signal plate engaging said plunger being adapted to depress the same when said plate is rocked downward and functioning to return the plate by the upward pressure of said plunger, a fluid operated dashpot within said housing for retarding the upward movement of said plunger so as to prevent the swinging of the plate beyond its upright position, and a partition separating the fluid in said dashpot from the space in the upper portion of said housing whereby lubricating fluid for said cam and plunger may be retained in said housing separate from the fluid of said dashpot.

5. A traffic signal comprising a bed plate having a central upwardly extending hollow housing integral therewith, a signal plate normally extending perpendicular to said bed plate and bifurcated to embrace said hollow housing, a shaft extending from the furcations of said signal through said hollow housing to form a pivot permitting rocking of said signal plate from a perpendicular position to a position parallel and adjacent to said bed plate, a cam mounted on said shaft centrally thereof, a cylindrical housing beneath said bed plate and communicating with said hollow housing, a plunger in said cylindrical housing having its upper end bearing against said cam its lower portion constituting a piston movable in said cylindrical housing, a spring for pressing said plunger upward, a check valve permitting the free passage of fluid from beneath said piston to the space above the same but preventing return-movement of said fluid, a restricted passage permitting a slow return of fluid from above the piston to the space beneath the same, and an apertured head through which said plunger passes separating the space above the piston from the space higher up in said cylinder whereby lubricating fluid may be held in said upper space and within said hollow housing, said plunger having passages therethrough permitting movement of said lubricating fluid past the same during the reciprocation of the plunger.

6. A traffic signal comprising a bed plate, a signal plate pivotally mounted on said bed plate and rockable from a perpendicular position to a position parallel and adjacent to said bed plate, a spring pressed plunger and cooperating cam for returning said signal plate to upright position, and a ramp on said bed plate clearing said signal plate in depressed position and adapted to raise a vehicle wheel to the level thereof.

7. A traffic signal comprising a bed plate, a signal plate pivotally mounted on said bed plate and rockable from a perpendicular position to a position parallel and adjacent to said bed plate, resilient means for returning said signal plate to its upright position after depression of the same, and means for positively retarding the speed of the return of said signal plate to its upright position thereby limiting the momentum thereof to be insufficient to carry beyond said upright position.
